UNITED STATES PATENT OFFICE.

CHARLES H. SCHURR, OF CLEVELAND, OHIO, ASSIGNOR TO THE LEES-BRADNER COMPANY, OF CLEVELAND, OHIO, A CORPORATION OF OHIO.

HOBBLING MACHINE.

Application filed December 7, 1923. Serial No. 679,127.

This invention relates to machines for hobbing gears.

One object of the invention is to provide an improved mechanism for feeding the work in either direction.

Another object of the invention is to provide relatively simple means for rotating the tool and work-piece in correlation to each other.

Another object of the invention is to provide an improved mounting for the tool, whereby it may be adjusted to different operative positions.

Other objects of the invention will be apparent to those skilled in the art to which my invention relates from the following description taken in connection with the accompanying drawings, wherein

Fig. 1 is a top plan view of a hobbing machine embodying my invention.

Fig. 2 is an end elevation of the machine.

Fig. 3 is an end elevation looking at the opposite end of the machine.

Fig. 4 is a front elevation of the machine.

Fig. 5 is a section on the line 5—5 of Figs. 1 and 7.

Fig. 6 is a section on the line 6—6 of Fig. 5.

Fig. 7 is a section on the line 7—7 of Fig. 5.

Fig. 8 is a section on the line 8—8 of Fig. 6.

Fig. 9 is a section on the line 9—9 of Fig. 5.

Fig. 10 is a section on the line 10—10 of Fig. 5.

Fig. 11 is a section on the line 11—11 of Fig. 4.

Fig. 12 is a schematic top view of my invention to show in simplified form the arrangement of the parts therefor and to facilitate its understanding.

Fig. 13 is a side view of an annular member shown also in Fig. 5 and Fig. 6.

Fig. 14 is a cross sectional view on the plane 14—14 of Fig. 5, this plane being the plane of the right hand face of the annular member as it appears in Fig. 5.

Fig. 15 is a side view of a collar shown also in Figs. 10 and 5.

Fig. 16 is a sectional view on the plane 16—16 of Fig. 5, the plane lying in the left-hand face of the collar 94 as it appears in Fig. 5.

In the drawings, 1 indicates as an entirety

a frame formed from one or more castings each fashioned in any desired shape to provide supports and bearings for the parts and elements of the machine herein to be described. The frame 1 preferably comprises 60 a main section 1^a resting on the floor, a standard or column 1^b fixed to the main section 1^a by cap screws 2 and a supplemental section 2^a, the preferred arrangement being such that the tool or hob carrying shaft or spindle 2', to be later referred to, is disposed vertically, or substantially vertically; but it will be understood that the frame section and column may be arranged so that this shaft may be supported in any other 65 desired position.

At one side, the frame section 1^a is provided with a base portion 3, having guides 4 for a slide 5. The slide 5 is shaped to provide a support for spaced bearings 6 in 70 which is supported a spindle 7, carrying an arbor 7^a and work-piece A. The spindle 7 is held in position by covers 8, bolted to the walls of the bearings 6 by cap screws 9. 75 Fig. 2 indicates a gear 10 fixed to the spindle 7 between the bearings (see dotted lines in Fig. 2). The gear 10 meshes with and is driven by a pinion 12 splined in any desired manner to a shaft 12', to which reference will later be made.

13, 14 indicate casing members, provided with hollow extensions 15, 16, respectively, to form housings and suitable bearings in which the shaft 12' rotates and in which the pinion 12 rotates and slides while maintained in mesh with the gear 10 during movement of the slide and gear 10 relative to the shaft 12'. The work-piece A is mounted on the work arbor 7^a carried by the spindle 7 and held against a shoulder formed by such reduced portion by a nut 17 (see Fig. 1). At 18 the slide 5 is provided with suitable ways for a supplemental slide 19, which carries a thrust arm or abutment 20.

The arm or abutment 20 is arranged to engage the work arbor 7^a beyond the work-piece A and on that side remote from the hob or tool B. The ways 18 preferably extend parallel to the axis of the work shaft. A suitable lock, indicated at 21, may be provided to secure the supplemental slide 19 to the slide 5 at the desired position; such lock having a member (not shown) fitting the slot 21^a formed in the slide 5 and engaging the walls thereof when the handle 21^b is 100 105 110

- turned. The supplemental slide 19 is preferably adjusted on the slide 5 by a shaft 22, having a hand wheel 23 and a pinion (not shown) engaging a rack 24 provided on the 5 slide 5.
- 25 indicates an arm depending from the rear end of the slide 5 and formed with an opening 26 in which fits one end of a feed screw 27, such end being suitably keyed in 10 the opening. The end of the screw 27 is reduced to form a shoulder 28, which is held against the inner face of the arm by a nut 29 screwed on the free end of the screw and engaging the outer face of the arm 25.
- 15 30 indicates a supporting member slidably engaging suitable ways 30^a mounted on the frame 1. The member 30 extends upwardly to provide a standard 31 and a head 32. The head 32 is of annular shape, to permit 20 a shaft 33, to be later referred to, to extend through it and form a bearing on which a housing 34 swivels for a purpose to be hereinafter described. The housing 34 comprises a sleeve member 34^a surrounding 25 the shaft 33 and rotatably engaging the head 32, a main casing member 34^b and a removable member 34^c. The main member 34^b and removable member 34^c are provided with bearings for the tool spindle 2' which 30 extends therethrough and carries at its free end the tool B. The bearings for the spindle 2' are so arranged that a gear 36 (preferably a worm gear) may be removably fixed to the spindle 2'.
- 35 The main casing member 34^b and sleeve member 34^a are shaped to enclose the worm gear 36 and a worm 37 splined on the shaft 33 and meshing with the worm gear 36 to drive it. One side wall of the casing mem- 40 ber 34^b is provided with an integral plate 38, which bears against the face 31^a of the standard 31 and is arranged to be adjustably fixed thereto, so that the housing or casing 34 may be swiveled on the head 32 to 45 position the tool spindle 2' at any desired angle to the vertical. To permit of such swiveling and adjustment, the plate 38 and housing 34 carry bolts 38^a which slide in arc-shaped recesses or slots 38^b formed 50 in the standard 31. By tightening the bolts 38^a, the heads thereof or washers interposed between the heads and the standard 31, will engage the latter and thus secure the plate 38 to the standard in any position of adjustment.

55 Adjustment of the housing 34 and tool spindle 2' may be effected in any desired manner. For illustrative purposes, I provide on the side wall of the sleeve 34 a worm 60 segment 32^a with which meshes a worm 32^b fixed to a shaft 32^c. The shaft 32^c is mounted in suitable bearings provided in the wall of the standard 31. The free end of the shaft extends outwardly (see Fig. 11) and has a 65 squared or other shaped end to adapt it to

a tool whereby it may be turned. If the bolts 38^a are loosened and the shaft 32^c, rotated, it will be seen that the housing 34 and shaft 2' may be moved about the shaft 33 to any desired position.

70

36^a indicates a suitable anti-friction thrust bearing interposed between the lower end of the hub for the gear 36 and the adjacent bearing.

The shaft 33 extends transversely of the 75 frame through the head 32 and sleeve 34^a of the casing 34 and carries the worm 37 which meshes with the worm gear 36 as shown in Fig. 1. The shaft 33 is supported at one end in bearings 39, provided in a 80 hollow boss 39^a carried by the rear wall of the supplemental frame section 2^a and at its opposite end in bearings 40 provided in a housing 41. The housing 41 comprises a hollow section 42 and a cup member 43, hav- 85 ing a tubular extension 44 which forms one bearing for the shaft 12^a. The section 42 and cup member 43 are provided with open ends closed by removable plates 45, 46, re- spectively. The section 42 and cup member 90 43 are preferably formed integrally with each other and with a bracket or arm 47, by means of which the housing 41 is rigidly supported on the column 1^b, the latter hav- 95 ing an extended portion 1^b' (see Fig. 3) for this purpose.

48, 49 indicate change gears in mesh with each other, preferably a worm and worm gear, the former being removably connected to the shaft 33 and the latter being remov- 100 ably connected to the shaft 12^a. Access to the change gears 48, 49, is permitted by the removable plates 45, 46.

50, 51, indicate loose and fast pulleys, respectively, for a suitable drive belt (not 105 shown). The pulley 51 is secured to the shaft 33 in any desired manner.

52 indicates a suitable belt shifter, preferably comprising an endwise movable rod 52^a, carrying a pair of lateral arms 52^b 110 adapted to engage the belt and shift it in a well-known manner. The rear end of the rod 52 is mounted in an opening formed in a lug 53 formed integrally on top of the supplemental frame section 2^a; the other end of the rod is slidably mounted in an opening formed in the the free end of an arm 54, preferably formed integrally with and extending upwardly from the housing 41.

115 It will now be apparent from the fore- 120 going description that when the belt is shifted to the fast pulley 51 the worms 37 and 48 on the shaft 33 will be turned; the worm 37 connecting through the worm wheel 36 will drive the tool spindle 2' and tool B; the worm 48 connecting through the worm wheel 49 will drive the shaft 12^a, pinion 12, gear 10, work spindle 7 and work piece A.

125 It will also be seen that the driving mech- anism for the tool spindle 2' and work 130

spindle 7 is very simple in that the tool spindle is directly geared to the power shaft 33 and that the work spindle is also geared to the same power shaft through a single 5 pair of reduction gears and a single pair of change gears. Furthermore, this construction in which the drive shaft 33 is arranged at a right angle with the shaft 12^a permits me to utilize a worm and worm gear 48 and 10 49 for the change gears between the directly connected power shafts 33 and 12^a to change the speed ratio between them easily and through a very wide range of ratios.

In my construction, either of the power 15 shafts 33, 12^a, may be connected with the source of power—the fast pulley; but by preference, I have shown such pulley on the shaft 33 so that the movement of the slide for the work-piece carrying shaft may be 20 effected in a simple manner. In the form of construction shown, the power shafts 33, 12^a, are arranged at right angles to each other, this arrangement permitting the use of simple driving connections between them.

25 The worm 37 is splined to the shaft 33, this arrangement being necessary to permit the slide 30 to be moved or adjusted on the ways 30^a to feed the tool to the work-piece A, without affecting the driving connections 30 (worm 37 and worm gear 36) between the power shaft 33 and cutter carrying shaft 2'. The slide 30 may be moved by a hand operated means.

35 56 indicates as an entirety means for driving a nut 57, which engages the feed screw 27, to move the slide 5 in either direction. The nut 57 comprises a sleeve having screw threads on its inner end and mounted to rotate in a suitable bearing 57^a provided in 40 the frame section 1^a (see Fig. 6). 58 indicates a bevel gear, the hub of which is keyed on the sleeve nut 57. 59 indicates a thrust bearing between the rear face of the bevel gear 58 and wall of the frame forming the 45 bearing for the sleeve. The end of the sleeve adjacent to the gear 58 has a flange 58^a to engage the outer end of the gear and cooperates with a nut 60, screwed on the opposite end of the sleeve to prevent endwise 50 movement of the nut 57 in either direction in its bearing 57^a. Due to the fact that the nut 57 is held against endwise movement, its rotation will cause endwise movement of the feed screw, which in turn will move the slide 55 5 in its guides.

Of the driving means 56, 61 indicates a shaft having a bevel gear 62 fixed to its outer end and meshing with the gear 58. The outer end of the shaft 61 is mounted in an 60 arm 61^a which is provided on a casing 61^b to be later referred to. The arm 61^a is bored to receive the shaft 61, as shown in Fig. 5. The bore of the arm 61^a is provided with one or more bearings 61^c (see Fig. 5) for the 65 outer end of the shaft. The inner end of

the shaft 61 is mounted in a bearing 63 carried by a cap plate 64. The inner end of the shaft 61 is reduced to form a shoulder 65 which abuts the end wall of the bearing 63 to prevent endwise movement of the shaft 70 toward the left as viewed in Fig. 5. Such movement is also prevented by the engagement of the hub of the gear 62 with the outer end of the arm 61^a. The gear 62 may be secured on the outer end of the shaft 61 by a nut 66. Movement of the shaft 61 in the opposite direction is prevented through the engagement of a shoulder 67 on the shaft 75 engaging one end of a clutch element 68, loose on the shaft 61 and engaging at its other end the inner end wall of the arm 61^a.

69 indicates a worm gear keyed to the clutch element 68, and arranged to operate therethrough to rotate the shaft in one direction, when it is driven in the manner 80 about to be described. As will later appear, the shaft 61 is driven by separate driving connections, indicated as an entirety at 70, 71, to rotate the shaft in one direction to move the slide 5 and work-piece thereon in 85 the feeding direction or to rotate it in the opposite direction to return the slide and work-piece to starting position. The power for operating the separate drive connections 70, 71, is preferably derived from the shaft 90 33, for which purpose a belt pulley 72 is connected thereto or to the fast pulley 51, so that when the latter is operated either of the connections 70, 71, may be driven.

The pulley 72 is arranged to drive a belt 100 (not shown) which runs around a pulley 73 loose on the shaft 61. In order to accommodate certain elements of one of the driving connections (70), bearing sleeves 74, 74^a, surround a portion of the shaft 105 61, the former sleeve constituting a race for an anti-friction roller bearing 75 on which the loose pulley 73 rotates. 76, 77 indicate pulleys respectively connected with the separate driving connections 70, 71. The pulleys 76, 77 are arranged at either side of the loose pulley 73 in position to have shifted to them the belt driven by the pulley 72, so that either of driving connections 110 70, 71, may be readily operated. 78 indicates as an entirety a belt shifting mechanism 115 (see Fig. 6) preferably constructed and arranged to shift the belt from the pulley 73 to either pulley 76, 77, but to operate automatically in the opposite direction when the slide 5 reaches the limit of its movement in either direction. The belt shifting mechanism 78 will be referred to later.

The driving connections 70 serve to feed the slide 5, and work-piece A supported thereon, relative to the tool B—toward the right as shown in Fig. 1. Of these connections, 79 indicates a sleeve shaft mounted on the bearing sleeve 74^a and keyed at its inner end in any desired manner to the 120 130

pulley 76. The other end of the shaft is suitably cut to provide a worm 80. 81, 82, indicate a pair of shafts each mounted in suitable bearings provided in the side walls 6 of the casing 61^b. At one side of the casing 61^b, the shafts 81, 82, extend laterally and carry at their free ends removable or change gears 81^a, 82^a, respectively, in mesh with each other. 81^b, 82^b, indicate a worm gear 10 and a worm respectively carried by the shafts 81, 82, and meshing with the worm 80 and worm gears 69 respectively (the latter being already referred to), whereby the power of the sleeve shaft 79 is transmitted 15 through the elements 80, 81^b, 81, 81^a, 82^a, 82, 82^b and 69 to rotate the clutch element 68. From the foregoing description, it will be seen that I have provided power transmitting elements in which two reductions in 20 speed and a change gear adjustment are provided for, so that any desired speed for the shaft 61 and through it the slide 5 can be obtained.

83 indicates a thrust bearing for the 25 sleeve shaft 79, mounted between a collar 79^a and the adjacent end wall of the casing 61^b. 84, 85, indicate thrust bearings provided for the shafts 81, 82, respectively. As shown in Fig. 6 the shafts 81, 82, are reduced 30 to form shoulders which rest against the bearings, and the latter are seated against the inner side wall of the casing 61^b. The opposite ends of the shafts 81, 82, project through the inner side wall of the casing 35 61^b and carry nuts or collars 86, suitably secured to the shafts, to prevent their movement outwardly. The remaining elements of the driving connections 70 comprise devices which are movable to cause a driving 40 or non-driving, relationship between the clutch element 68 and shaft 61 accordingly, as the belt is shifted on to the pulley 77 or from the pulley back on to the pulley 73 or pulley 76. Referring to these devices, 87 indicates a clutch element slidably fitting the shaft 61 and movable thereon to engage and disengage the clutch element 68. The outer end of the clutch element 87 is preferably flanged, as shown at 87^a, to provide a support for a pair of pawls 88 the inner ends of which project into recesses or notches 89 formed in a pair of combined key and thrust members, 90, to connect the clutch element 87 thereto, so that when the thrust members 50 87^a are moved in one direction, as will be later set forth, the clutch element will be moved with them. The pawls 88 preferably comprise a pair of inwardly extending lugs provided on a ring 88^a, bolted to the flange 87^a, as shown in Fig. 5. 91 indicates grooves formed in the shaft 61 and extending longitudinally thereof to receive the thrust members 90 and permit them to move endwise therein. The inner wall of the clutch element 87 is formed with longitudinally ex- 55 tending grooves 92 which receive the outer edges of the thrust members, thereby serving as keys to lock the clutch element 87 to the shaft 61, so that the power of the clutch member 87, when driven will be transmitted through the thrust members 90 to rotate the shaft 61. 92^a indicates a collar surrounding the shaft 61 and fixed thereto in any desired manner. 93 indicates a coiled spring interposed between the collar 92^a and the clutch element 87 or ring 88^a and normally tending to move the clutch element 87 into engagement with the clutch element 68, so that when the power is applied through the pulley 76, the power transmitting elements and devices just described, the shaft 61 will be driven in that direction which will effect movement of the slide 5 to feed the work-piece A relative to the tool B. 60 The driving connections 71 for returning the slide 5 and work-piece A to the starting position are preferably of a character to insure relative quick movement of the slide, for which purpose such connections are connected directly to the shaft 61. Of these connections, 94 indicates a collar fitted to the shaft 61 so as to rotate thereon and keyed in any desired manner, as shown at 95, to the hub of pulley 77 so as to be driven thereby. 96 indicates recesses formed in and extending longitudinally of the inner wall of the collar 94 and arranged to receive the combined key and thrust members 90, whereby the latter serve as a driving connection between the collar 94 and shaft 61. The recesses 96 have a width greater than the width of the members 90 and their opposite side walls are so arranged that the collar 94 may rotate on or move relative to the shaft 61 a short distance before the key members will 65 engage the side walls of the recesses and thereby transmit the rotative power of the collar to the shaft 61. 97 indicates a projection formed on the end of the collar 94 and fitting within recesses 98 formed in an annular member 99 slidably fitting the shaft 61 and formed with grooves 100 aligned with the grooves 91 to receive the keys 90, whereby the latter lock the annular member and shaft together against relative rotative 70 movements. The walls of the projections 97 and recesses 98 therefor are inclined so as to operate as cams. Accordingly, if the collar 94 is rotated on the shaft 61, it will be seen that the cam walls of the projections 97 engaging the walls of the recesses 98 will coact therewith to effect a sliding of the annular member 99 endwise of the shaft 61. As the adjacent ends of the thrust members 90 are provided with shoulders 101 which engage the end wall of the annular member 99, it will be seen that the movement of the latter endwise of the shaft will impart a corresponding movement to the keys 90, which in turn, acting through the pawls 88, 75 100 105 110 115 120 125 130

will move the clutch element 87 and release it from the clutch element 68. The rotation of the collar 94 on the shaft 61 is provided for by making the recesses 96 for the key members 90 wider than the width of the latter, as already described, so that when the belt is moved on to the pulley 77, it first rotates the collar on the shaft 61 until the key members engage the remote side walls of the recesses, following which the pulley, acting through the collar 94, will drive the shaft 61 in a direction opposite to that when the driving connections 70 are connected to it. The rotative movement of the collar 94 on the shaft 61, determined by the width of the recesses 96, is sufficient to move the annular member and keys far enough to effect a disengagement of the clutch elements 68, 87, before the keys engage the side walls of the recesses and through them effect or complete the driving connections from the pulley 77 to the shaft 61. Upon the shifting of the belt from the pulley 77 back to the loose pulley 73, the spring 98 will move the clutch element 87 into engagement with the clutch element 68 and through the former element move the keys endwise; and the keys in turn, through the annular member 99 and its cam will rotate the collar 94 on the shaft 61 in the opposite direction, thereby restoring these elements to normal position.

Of the belt shifting mechanism 78, 102 indicates a belt engaging member preferably comprising a sleeve 102^a having spaced arms 103 disposed at opposite sides of the belt so as to engage therewith to move it in either direction (see Fig. 6). 104 indicates an operating rod to which the belt engaging member is secured in any desired manner. 104 is preferably mounted to move endwise in either direction so as to move the belt from the pulley 73 to either pulley 76, 77. The rod 104 is mounted in suitable bearings in the frame members and extends to a point beyond the front of the frame, where it is provided with a handle 105. 106 indicates a collar fixed to the rod 104 by a set screw or other suitable device. 107 indicates springs coiled around the rod 104, each interposed between one side of the collar 106 and the adjacent wall of the frame 1—see Fig. 6. The springs 107 acting on the collar 106 serve to maintain the latter midway between the opposing walls of the frame, so that the belt engaging member 102 is held in its mid-position, that is, with the belt guided to the pulley 73. Accordingly, if the rod 104 is moved endwise in either direction to shift the belt to the pulley 76 or 77, one of the springs 107 will be compressed so that upon the release of the rod, such spring will return the rod to its normal position and thus effect the automatic shifting of the belt from the pulley 76 or 77 back to the loose pulley 73. 108 indicates a pair of notches formed in the rod 104. 109 indicates a lock and release member, preferably comprising a rod slidably mounted in a bearing 110 formed in a plate 111, which is bolted on the side wall of the frame section 1^a—see Fig. 2. The rod 109 is preferably disposed at right angles to the operating rod 104. The upper end of the rod 109 is preferably provided with cam surfaces 112 and these surfaces, when the rod 109 is in its raised or normal position, are disposed in the path of movement of a pair of spaced cams 113 and 113^a carried by the slide 5. The lower end of the rod 109 may be provided with a foot-engaging member 114 by means of which the operator can conveniently move the rod downwardly when it is desired to release the rod 104 and to stop the driving connections 70 or 71. The lower end of the wall for the bearing 110 is enlarged to form a chamber 110^a for a spring 115, preferably coiled around the rod 109. One end of the spring bears against a hollow plug 116, screwed into the open end of the chamber 110^a, and the opposite end of the spring engages a collar provided on the rod 109 and acts therethrough normally to push the rod upwardly to position the cam surfaces 112 in the path of movement of the cams 113, 113^a. 117 indicates a notch or cut-away portion formed in one side of the rod 109, and arranged so as to permit the rod 104 to be moved endwise when the rod 109 is depressed or lowered. Below the notch 117 the rod is provided with a lug 117^a which enters one of the notches 108 when the rod 104 is moved in either direction. By preference, the rod 104 is cut away to form an angle shaped recess the wall of which slides on the lug 117^a as the rod is moved. As shown in Figs. 6 and 8, the rods 104, 109, are so positioned or supported that one intercepts the other, the purpose being to effect the locking and releasing of the rod 104 by the rod 109, as will be understood from the following description: Figs 6 and 8 illustrate the rod 104 in normal position and disposed in the cut-away portion 117. If now the rod 104 is moved endwise to bring one of the notches 108 in alignment with the lug 117^a on the rod 109, the latter will be operated upwardly under the influence of the spring 115 to the position shown in Fig. 2, and by the engagement of the lug 117^a with a side wall of the notch 108, will lock the rod 104 in operated position with one of the springs 107 compressed. As the notches 108 are spaced so that movement of the rod 104, as just described, will shift the belt to one of the pulleys 76, 77, it will be seen that the slide 5 will be put in operation, and as the work-piece A and tool B are driven in correlation to each other through the shafts 33 and 12^a, it will be seen that the 130

machine will be put in operation. Assuming that the belt has been shifted to the pulley 76, the drive connections 70 will be operated and the slide 5 moved in the feeding direction or toward the right as shown in Fig. 2. As the end of this movement is approached, the cam 113 engages the adjacent cam surface 112 and pushes the rod 109 downwardly, against the tension of the 50 spring 115, which movement will bring the notch 117 into alignment with the rod 104 and permit its endwise movement under the influence of the spring 107. By operating the rod 104 to its other position, to shift 10 the belt to the pulley 77, the slide 5 will be returned to starting position, at which time or as it approaches such position, the cam 113^a will operate the rod 109 and release the rod 104 in the manner already described. 15 From the foregoing description, it will be seen that I have provided relatively simple means for setting the slide 5 in operation and for automatically stopping it at the end of its movement in either direction. 20 118 indicates a casing or housing for the change gears 82^a, 81^a. The casing 118 comprises a pair of members 118^a, 118^b, the former being secured to the frame member by cap screws 119 and the latter being removably secured to the casing member 118^a by a pair of devices 120. 25 121 indicates a shaft mounted in a sleeve 122. The sleeve 122 is provided with a flange 122^a, which is secured in any desired manner to the frame member 1^a—see Fig. 30 2. The sleeve 122 is mounted in an opening 123 formed in the frame member 1^a. 124 indicates a bushing for the shaft fixed in the sleeve in any desired manner. The inner end 40 of the shaft 121 is reduced to form a shoulder 125 against which a bevel pinion 126 is seated. The pinion is held in position on the inner end of the shaft by a nut 126^a. The pinion 126 meshes with the pinion 55 127 and is arranged to drive the latter when the shaft 121 is rotated. The outer end of the shaft 121 is squared or otherwise shaped to receive a crank (not shown) by means of which the shaft is rotated, thus providing 60 a means for moving the slide 5 by hand, when desired. 127, 127^a, indicate a pair of collars or rings mounted on the shaft 121 and forming abutments for a spring 128 coiled around the shaft 121. The outer ring 55 127^a is slidable on the shaft so that it may be engaged by the crank and moved inwardly against the tension of the spring 128 when the crank is positioned on the squared end of the shaft. So long as the crank is 70 held by the operative, on the squared portion of the shaft, the ring 127^a will be held against movement outwardly, but upon release of the crank by the operative, the spring 128, acting through the ring 127^a, 75 will slide or push the crank off the outer

end of the shaft 121. To prevent the ring 127^a from being pushed by the spring 128 out of the sleeve 122, the outer end thereof is provided with an inwardly extending flange 129, which forms a stop for the ring. 80

The slide 30 is moved into cutting position and then out of engagement with the work by any suitable means, but preferably by means of a feed screw (not shown) operated by a crank wheel 130, the operations 85 of which are controlled by a rod 131 fixed to the side 30^a and a lug 132 fixed to the rim of the wheel 130.

133 indicates a wheel or pulley fixed to an extended end of the shaft 33 and driving a belt (not shown) which runs around a pulley 134 fixed to the shaft 135. The shaft 135 is mounted in a bracket 136 and is geared or connected to a pump, indicated generally at 137, having a supply pipe 138 and a delivery pipe 139 for a cooling fluid for well known purposes. 90

From the foregoing description, it will be seen that I have provided a relatively simple form of construction for driving the tool and work spindles, while permitting feeding of the latter spindle and angular adjustment of the former as well as its movement toward and from the work. In this connection I provide two shafts at angles to each other—preferably at right angles, which arrangement admits of the use of worm gears. As access to these gears is provided for, they may be removably connected to their respective shafts. As a result, they may be readily removed and others substituted to change the ratio of rotation of one shaft relative to the other. It will also be seen that the tool spindle is mounted to swing about the axis of one of these shafts so that it may be adjusted in a plane that is parallel to the work carry spindle to any desired angle according to the character of the work to be cut. 100

To those skilled in the art to which my invention relates, many alterations in construction and widely differing embodiments and applications of the invention will suggest themselves without departing from the spirit and scope thereof. My disclosures and the description herein are purely illustrative and are not intended to be in any sense limiting. 105

What I claim is:

1. In a hobbing machine, a drive shaft connected to a source of power, a tool spindle, a driven gear on the tool spindle and a driving gear on the drive shaft meshing therewith to drive the tool spindle, a supplemental shaft, a driven gear on the supplemental shaft and a second driving gear on the drive shaft meshing therewith to drive the supplemental shaft, a work spindle, a driven gear on the work spindle and a driving gear on the supplemental shaft 110 115 120 125 130

being adjustable by adjusting the tool spindle toward the work spindle in a direction parallel to the drive shaft.

9. In a hobbing machine, a drive shaft, a tool spindle, a driven gear on the tool spindle and a driving gear on the drive shaft meshing therewith to drive the tool spindle, a work spindle at substantially a right angle to the drive shaft, driving connections including a second driving gear on the drive shaft whereby the work spindle is driven from the drive shaft, the tool spindle being adjustable around the axis of the drive shaft in a plane parallel to the axis of the work spindle.

10. In a hobbing machine, a drive shaft, a tool spindle, a driven gear on the tool spindle and a driving gear on the drive shaft meshing therewith to drive the tool spindle,

20 a supplemental shaft, a driven gear on the supplemental shaft and a second driving gear on the drive shaft meshing therewith to drive the supplemental shaft, a work spindle, driving connections between the supplemental shaft and the work spindle for driving the work spindle, the tool spindle being adjustable around the axis of the drive shaft in a plane parallel to the axis of the work spindle.

30 11. In a hobbing machine, a drive shaft, a tool spindle, a driven gear on the tool spindle and a driving gear on the drive shaft meshing therewith to drive the tool spindle, a supplemental shaft, a driven gear on the supplemental shaft, and a second driving gear on the drive shaft meshing therewith to drive the supplemental shaft, a work spindle at substantially a right angle to the drive shaft, driving connections between the supplemental shaft and the work spindle, the tool spindle being adjustable around the axis of the drive shaft in a plane parallel to the axis of the work spindle.

40 12. In a hobbing machine, a drive shaft, a tool spindle, a driven gear on the tool spindle and a driving gear on the drive shaft meshing therewith to drive the tool spindle, a supplemental shaft, a driven gear on the supplemental shaft and a second driving gear on the drive shaft meshing therewith to drive the supplemental shaft, a work spindle substantially parallel to the supplemental shaft and substantially at a right angle to the drive shaft, a driven gear on the work spindle and a driving gear on the supplemental shaft meshing therewith to drive the work spindle.

50 13. In a hobbing machine, a drive shaft, a tool spindle, a driven gear on the tool spindle and a driving gear on the drive shaft meshing therewith to drive the tool spindle, a work spindle at substantially a right angle to the drive shaft, driving connections including a second driving gear on the drive shaft whereby the work spindle is driven

from the drive shaft, the tool spindle being adjustable around the axis of the drive shaft in a plane parallel to the axis of the work spindle and adjustable toward and from the work spindle in a direction parallel to the drive shaft.

70 14. In a hobbing machine, a drive shaft, a tool spindle, a worm gear on the tool spindle and a worm on the drive shaft meshing therewith to drive the tool spindle, a supplemental shaft, a worm wheel on the supplemental shaft and a second worm on the drive shaft meshing therewith to drive the supplemental shaft, a work spindle, connections between the supplemental shaft and the work spindle to drive the work spindle, the tool spindle being adjustable around the axis of the drive shaft in a plane parallel to the axis of the work spindle.

80 15. In a hobbing machine, a drive shaft, a tool spindle, a worm gear on the tool spindle and a worm on the drive shaft meshing therewith to drive the tool spindle, a supplemental shaft, a worm gear on the supplemental shaft and a second worm on the drive shaft meshing therewith to drive the supplemental shaft, a work spindle substantially parallel to the supplemental shaft and substantially at a right angle to the drive shaft, a gear on the work spindle and a gear on the supplemental shaft meshing therewith to drive the work spindle.

90 16. In a hobbing machine, a drive shaft, a tool spindle, a driven gear on the tool spindle and a driving gear on the drive shaft meshing therewith to drive the tool spindle, a work spindle at substantially a right angle to the drive shaft, driving connections whereby the work spindle is driven from the drive shaft, the tool spindle being adjustable around the axis of the drive shaft in a plane parallel to the axis of the work spindle, the tool spindle being adjustable toward and from the work spindle in a direction parallel to the drive shaft, and the work spindle being movable in the direction of its axis relatively to the tool spindle with a feeding movement.

100 17. In a hobbing machine, a drive shaft, a tool spindle, a worm gear on the tool spindle and a first worm on the drive shaft meshing therewith to drive the tool spindle, a work spindle at substantially a right angle to the drive shaft, driving connections including a second worm on the drive shaft whereby the work spindle is driven from the drive shaft, the tool spindle being adjustable around the axis of the drive shaft in a plane parallel to the axis of the work spindle, and the worm wheel being correspondingly adjustable on the first worm around the said axis and in engagement therewith at all adjusted positions.

110 In testimony whereof, I have hereunto subscribed my name.

CHARLES H. SCHURR.
